UNITED STATES PATENT OFFICE.

SETH A. CRONE, OF NEW YORK, N. Y.

BRAKE-BEAM FOR ELECTRIC AND OTHER CARS.

No. 832,599.

Specification of Letters Patent.

Patented Oct. 9, 1906.

Application filed April 25, 1906. Serial No. 313,683.

To all whom it may concern:

Be it known that I, SETH A. CRONE, a citizen of the United States, and a resident of New York city, in the county of New York and State of New York, have invented certain new and useful Improvements in Brake-Beams for Electric and other Cars, of which the following is a specification.

The invention relates to improvements in brake-beams for electric and other cars; and it consists in the novel features and construction hereinafter described, and particularly pointed out in the claims.

Brake-beams of the class to which my invention pertains comprise a rolled body-beam of suitable length, brake-heads of suitable construction on the ends thereof, and a fulcrum for the brake-lever; and my invention has for its object to produce a novel fulcrum for use in such beams, said fulcrum being capable of being firmly and quickly applied to the beam and of sustaining the great strains to which fulcrums in modern high-speed electric cars are subjected, the fulcrum of my invention being of forged metal bent into the desired shape, the parts of the fulcrum while being given such shape not being unduly stretched or weakened. The fulcrum of my invention comprises side members to receive between them the brake-lever, flanges to lap around the flange of the body-beam, and flanges laterally spread apart to engage the web of the body-beam, said web-flanges being out of vertical alinement with each other and the entire fulcrum being preferably, though not necessarily, formed of one integral bar of forged metal or one integral merchant-bar. It is usually necessary in modern electric-car equipment that the sides of the fulcrum stand at right angles to the longitudinal line of the body-beam, and in accordance with my invention I am enabled to give these sides such angle and secure the spreading apart of the web-flanges without unduly weakening or punishing the metal while giving it the proper outlines to secure an efficient fulcrum, the production of which is the object of my invention.

The invention will be fully understood from the detailed description hereinafter presented, reference being had to the accompanying drawings, in which—

Figure 1 is a detached top view of a fulcrum constructed in accordance with and embodying the invention. Fig. 2 is an outer end view of same, taken from the right-hand

end of Fig. 1 and indicating by dotted lines a portion of the body-beam. Fig. 3 is a transverse section through a brake-beam having the fulcrum applied thereto, the fulcrum being shown in side elevation; and Fig. 4 is a detached face view, partly broken away, of a bar of forged metal which I utilize in the production of the fulcrum shown in Fig. 1.

In the drawings, 10 designates a portion of the usual body-beam, and 11 the novel fulcrum of my invention, which is applied centrally on one edge of the beam and in the form shown is in one integral bar of forged metal folded at its center to form the side members 12 13, which are apertured, as at 14, to receive the pin for the brake-lever (not shown) and stand at a right angle to the longitudinal line of the beam 10, and at the inner ends of which sides the end portions of the bar have a twist or a one-quarter turn in opposite directions from said sides, whereby curved flanges 15 are formed extending from said sides, which are vertical, to the horizontal upper and lower edges of the inner flange 16 of the body-beam. Beyond the flanges 15 the end portions of the fulcrum have the flanges 17 and 18, the latter engaging the web of the beam 10 and the flanges 17 the faces of the flange 16 at the sides of said web. The flanges 17 extend inwardly transversely of the body-beam and substantially at right angles to the longitudinal line thereof, while, as shown in Fig. 1, the flanges 18 flare outwardly in a direction from each other and from the inner edges of said flanges 17. The flanges 18 are, as shown in Figs. 1 and 2, set outwardly beyond the vertical planes of the sides 12 13, and said flanges 18 are secured to the web of the body-beam by rivets 19.

I am enabled to form the fulcrum in the special outline shown and above described without unduly stretching or weakening the metal in the formation of the flanges 15 by making it from a forged bar 20, Fig. 4, having its end portions reversely disposed in the outline shown in Fig. 4, each of said end portions comprising a laterally-deflected section 21 and an outer section 22, which is at an angle to the body of the bar 20 and inclines reversely at an angle to the section 21. The sections 21 22 may be formed on the ends of the bar 20 by means of dies in a press, said dies bending the bar on its edges to produce said sections. I indicate in Fig. 4 as closely as possible by dotted lines 23 24, respectively, the lines on which the reversely-disposed end

portions of the bar 20 will be bent to form the flanges 17 18, the dotted lines 23 denoting the line of the fold of the bar at the horizontal outer edge of the beam-flange 16 and the dotted lines 24 denoting the line of the fold of the bar at the adjoining edges of the flanges 17 18. A portion of the sections 21 of the bar is utilized in the formation of the flanges 15, and another portion of said sections is utilized in the formation of the flanges 18, while that portion of said sections 21 intermediate the lines 23 24 finally forms the flanges 17. In the production of the fulcrum from the bar 20 the latter is first reversely bent on edge at its ends to produce the reverse sections 21 22, then each end of the bar is bent to form the flanges 15 17 18, and finally the bar is folded at its middle to produce the sides 12 13.

20 I prefer to form the entire fulcrum in one integral piece from a merchant-bar on account of the manifest superiority of the integral structure; but it is obvious that with less advantage the fulcrum sides may be in separate pieces, and, if desired, riveted together at the outer end 25 of the fulcrum in the several ways known to the art—as, for illustration, as shown in Patent No. 720,677, dated February 17, 1903.

30 In accordance with my present invention I am enabled to produce a fulcrum from forged metal and without unduly stretching or weakening the same, having sides which stand at right angles to the length of the body-beam, and are provided at their inner ends with flanges 15, 17, and 18 to engage said beam, the flanges 18 being spread apart, so that they extend outwardly from each other and beyond and at right angles to the 40 vertical planes of said sides.

What I claim as my invention, and desire to secure by Letters Patent, is—

1. A brake-beam fulcrum of forged bar metal having vertical side members 12, 13, 45 flanges 15 curving therefrom to the horizontal edges of the beam-flange, and flanges 17, 18 respectively engaging said beam-flange and the web of the beam, said flanges 18 being extended outwardly in a direction from each 50 other and at right angles from said side members; substantially as set forth.

2. A brake-beam fulcrum in one integral piece of forged bar metal folded at its middle portion and having vertical side members 12, 13, flanges 15 curving therefrom to the horizontal edges of the beam-flange, and flanges 17, 18 respectively engaging said beam-flange and the web of the beam, said flanges 18 being extended outwardly in a direction from each other and at right angles from said side 55 members; substantially as set forth.

3. A brake-beam fulcrum of forged bar metal comprising side members to receive the brake-lever and having at their inner ends the flanges 15 curving therefrom to the horizontal edges of the beam-flange and flanges 17, 18 respectively engaging said beam-flange and the web of the beam, said flanges 18 being extended outwardly in a direction from and beyond each other, and said side members having at their inner ends the laterally reversely disposed end portions for the formation of said flanges and each comprising a laterally-deflected inner section 21 and an outer reversely-deflected section 22 disposed 65 at an angle to the body of the bar and also to said section 21; substantially as set forth.

4. A brake-beam fulcrum in one integral piece of forged bar metal folded at its middle portion and comprising side members to receive the brake-lever and having at their inner ends the flanges 15 curving therefrom to the horizontal edges of the beam-flange and flanges 17, 18 respectively engaging said beam-flange and the web of the beam, said 80 flanges 18 being extended outwardly in a direction from and beyond each other, and said side members having at their inner ends the laterally reversely disposed end portions for the formation of said flanges and each 85 comprising a laterally-deflected inner section 21 and an outer reversely deflected section 22 disposed at an angle to the body of the bar and also to said section 21; substantially as 90 set forth.

95 Signed at New York city, in the county of New York and State of New York, this 23d day of April, A. D. 1906.

SETH A. CRONE.
